UNITED STATES PATENT OFFICE.

TYRE C. HUGHES, OF KANSAS CITY, MISSOURI.

MIXING-MACHINE.

No. 876,356.

Specification of Letters Patent.

Patented Jan. 14, 1908.

Application filed March 29, 1904. Serial No. 200,511.

To all whom it may concern:

Be it known that I, TYRE C. HUGHES, a citizen of the United States, residing at Kansas City, in the county of Jackson and State 5 of Missouri, have invented new and useful Improvements in Mixing-Machines, of which the following is a specification.

My invention relates to improvements in mixing machines adapted to be used in mixing concrete, building or paving materials, 10 wet or dry, plastic materials, such as mortar, ore samples, or paints, dyes, oils or similar materials.

My invention is so constructed as to permit 15 the discharge of the mixed materials during the feeding operation, thus rendering the operation of the machine practically continuous.

My invention provides further a mixing 20 vessel having a single opening through which the materials to be mixed are both received and discharged. With such a construction the materials are discharged in an order the reverse of that in which they are fed into the 25 vessel, thus effecting a much more thorough commingling of the different ingredients than is attained by machines in which the material is taken in to a mixing vessel at one end and discharged at the opposite end 30 thereof.

My invention provides further means by 35 which one or more vessels, provided each with a single opening for receiving and discharging the materials to be mixed, is revolved in two planes disposed at an angle to each other, the vessels being disposed so that when one is receiving the other is discharging.

My invention also provides mixing blades 40 on the inner peripheries of the mixing vessels and disposed so that when the vessel is in the feeding position, the blades will throw the material toward the closed end of the vessel in which the material is being fed, and also toward the axis of the vessel, while in 45 the vessel that is being discharged the blades will throw the material toward the opening as well as toward the axis.

My invention provides other novel features hereinafter fully described and claimed.

50 In the accompanying drawings illustrating my invention, Figure 1 is a top view of the mixing machine, the propelling engine being omitted from the view. Fig. 2 is a side elevation view. Fig. 3 is an end elevation view, showing the machine in position for both feeding and discharging. Fig. 4 is a

central vertical sectional view of the two vessels and parts connected therewith. Fig. 5 is a cross section taken on the dotted line *a*—*b* in Fig. 4, the supporting frame being omitted. Fig. 6 is a sectional detail view of a portion of the gearing employed for revolving the vessels around their axes. Fig. 7 is a central longitudinal sectional view of the clutch mechanism. Fig. 8 is a cross section 65 on the line *c*—*d* of Fig. 1.

Similar characters of reference indicate similar parts.

1 denotes the base upon the upper side of which is mounted a boiler 2, engine 3, and 70 three vertical bearings 4, 5 and 6. The revolute frame in which are mounted the mixing vessels comprises two vertical gear wheels 7 and 8 connected by transverse bars 9 and 10. The wheels 7 and 8 are provided respectively 75 with curved arms 11 and 12, which are connected respectively by diametrical arms 13 and 14, provided respectively with trunnions 15 and 16 rotatively mounted respectively in the bearings 4 and 5. Rotation of the frame 80 is provided by means of two pinions 17 and 18 mounted on and rotatable with a horizontal shaft 19, the pinions meshing respectively with the gears 7 and 8. Rotation of the shaft 19 is obtained in the manner hereinafter described. A shaft 20 located parallel 85 with the gears 7 and 8 and in a plane coincident with the axes thereof, has its bearings in oppositely disposed bars 10. Two collars 21 on the shaft 20 disposed one adjacent the inner side of each bar 10 are provided respectively with set screws 22 which engage the shaft 20 and prevent endwise movement in the bars 10 of the shaft 20.

The shaft 20 is disposed in the axis of a 95 barrel or drum A, comprising a transverse member 23 consisting preferably of a large disk uniting two smaller ends 33 and 34 of the barrel, and serving as a transverse partition for dividing the barrel into two chambers or vessels. The member 23 is provided with peripheral teeth which engage a pinion 24 secured upon a shaft 25 disposed parallel with shaft 20 and having its ends rotatively mounted in the arms 12. The plate 23 is 100 keyed to the shaft 20 so that the barrel A will rotate with said shaft. Secured on the shaft 25 is a bevel gear wheel 26 which meshes with a bevel gear wheel 27 secured on and rotatable with a horizontal shaft 28, the ends 105 of which are rotatively mounted in the bearing 6 and in the hollow bore of the trunnion 110

16. On one end of the shaft 28 is secured a disk 29 having a crank pin 30 to which is pivoted a connecting rod 31, which is also connected in the usual manner to the piston rod 32 of the engine 3.

17. The mixing vessels 33 and 34 are mainly cylindrical and converge at outer and opposite ends, the opposite ends of the vessels 33 and 34 having openings for receiving and discharging alternately the material to be mixed. On the inner periphery of each vessel or chamber 33 and 34 are provided a plurality of radially disposed mixing blades 35, which when the barrel A is in one inclined position throws the material toward the closed end of the vessel that is uppermost, and toward the open end of the vessel that is lowermost.

18. A chute 36 is pivoted to a vertical post 37 which is provided with a rest 38 for supporting the chute when the same is in position for feeding. The disposition of the chute 36 is such that, when the vessels are revolved with the frame in the direction of the movement of the hands of a clock, as shown in Fig. 3, the chute can be upturned to permit the vessels to pass it. While in the feeding position, as shown in Fig. 3, the chute will extend into the upper vessel 33.

19. The shaft 19 has its ends rotatively mounted in the bearings 4, 5 and 6. Rotatable with and mounted on the shaft 19 is a clutch cone 39 which is slidable lengthwise on the shaft 19 and is adapted to have one conical end enter and clutch by friction a sprocket wheel 40 which is revoluble, when disengaged from the cone, upon the shaft 19.

20. From the above description it will be seen that the mixing barrel or drum A is mounted for rotation around its own axis as well as around the axis of the shaft 15 and at right angles to its own axis. The first movement is continuous and the second movement capable of interruption by means of the clutch 39. 25. The first movement gives the principal mixing effect, and the second movement serves to bring the barrel A into the charging and discharging positions shown in Fig. 3. The charge to be mixed having been placed in the upper vessel of the inclined barrel A, the clutch 39, being at this time out of gear, is thrown in, and the barrel or drum A at once begins to rotate clockwise, carrying the charged compartment over trunnion 15 30. while continuing its rotation around its own axis. This rotation about trunnion 15 is continued until the charged compartment is brought into the discharging position, at which the other compartment is in the charging position. At this time the clutch 39 is then thrown out and the series of events just described is repeated, so as to charge, mix and discharge the other compartment.

21. Rotation is imparted to the sprocket wheel 40 by means of a sprocket chain 41

which embraces also a sprocket wheel 42 mounted on and rotatable with the shaft 28. To shift the cone 39 into or out of engagement with the sprocket wheel 40, a lever 43 pivoted to the bearing 6 is provided with a bifurcated lower end which engages an annular peripheral groove 44 in the cone 39. By properly swinging the lever, the cone 39 may be made to engage the sprocket wheel 40 and imparting thus rotation from the shaft 28 to the shaft 19.

22. A more specific description of the operation of the parts is as follows:—The engine 3 is caused to rotate the shaft 28 by means of the mechanism described, the lever 43 being positioned so that the cone 39 will engage the sprocket wheel 40 and cause rotation to be imparted to the shaft 19, by means of the chain 41 and sprocket wheel 42. The pinions 17 and 18 rotating with the shaft 19 will impart rotation to the frame by means of the gears 7 and 8, thus swinging the vessels 33 and 34 around in a plane perpendicular to the trunnions 15 and 16. When the vessel 33 and the vessel 34 are in the position inclined to the horizontal, as shown in Fig. 3, the lever 43 is moved so as to release the cone 39 from the sprocket wheel 40, and the frame carrying the mixing vessels 33 and 34 will cease revolving. The material to be mixed may then be poured into the upper vessel 33 through the chute 36. During this time the shaft 28 in revolving revolves the vessels 33 and 34 around their axes by means of the bevel gears 26 and 27, pinion 24 and transverse plate or member 23. The material in the vessel 33 will be picked up by the radial blades 35 and thrown toward the axis and the closed end of the said vessel. When the vessel 33 is filled, the vessel 34 will have been emptied, the blades 35 in the vessel 34 throwing the material toward the axis and the open end of the said vessel 34. The lever 43 is then thrown so as to cause the rotation of the gears 7 and 8 on the trunnions 15 and 16, thus revolving the frame as already described and reversing the positions of the vessels 33 and 34 from the positions shown in Fig. 3. At this time the vessel 34 will be receiving and the vessel 33 discharging. The material first entering the vessel will be the last to be discharged, thus most thoroughly commingling the different ingredients that are being mixed. It will be noted that with the blades 35 disposed radially, they will facilitate by their inclination from the horizontal the discharge as well as entrance of the material. The time required for reversing the positions of the vessels 33 and 34 being comparatively short, the operation of the machine will be practically continuous.

23. If it is desired to use other means for driving the shaft 28 than that shown, a pulley 45 is provided mounted on and rotatable with the shaft 28. To this pulley a belt connected

with some suitable driving pulley may be connected.

By maintaining the vessels in the position shown in Fig. 3, during the feeding and discharging thereof, the inclination of the vessels facilitates the rapid movement of the ingredients within the vessels, and thus accomplishes with the aid of the rotary movement of the vessels around their axes, a more rapid and thorough commingling of the materials than is attained with vessels which are horizontally disposed during rotation.

My invention is not confined in its scope to the particular means for rotating the vessels nor the exact means shown for rotating the frame supporting the vessels. The movement of these parts may be obtained in other ways than those shown. So also may the construction of the vessels be other than the form illustrated. Various other modifications of my invention may be resorted to without departing from its spirit and scope.

Having thus described my invention, what I claim and desire to secure by Letters Patent, is:—

1. In a mixing machine, the combination with an axial supporting shaft, of two vessels mounted on said shaft each vessel being provided with a single opening for receiving and discharging the contents thereof, the openings being disposed in the ends of the vessels distant from each other, means for rotating said vessels around the axis of the supporting shaft, and means for rotating the vessels in a plane at an angle to the plane of rotation around the axis of the shaft.

2. In a mixing machine, the combination with two mixing vessels disposed with their axes in line and having each in its outer end a single opening for receiving and discharging the contents of the vessel, of an axial shaft on which the vessels are mounted and rotatable therewith, means for rotating said shaft and said vessels, a frame in which the shaft is rotatively mounted, and means for revolving the frame together with said vessels and shaft in a plane at an angle to the plane of rotation around the axis of the shaft.

3. In a mixing machine, the combination with a rotatable shaft, of a transverse member mounted thereon and rotatable therewith, two mixing vessels mounted on said transverse member and having their axes coincidental with the axis of the shaft, each vessel having at its outer end a single opening for receiving and discharging its contents, means for rotating said transverse member, said shaft and said vessels around the axis of the shaft, a frame supporting said shaft, and means for revolving said frame in a plane at an angle to the plane of revolution of said vessels around the axis of the shaft.

4. In a mixing machine, the combination with a rotatable shaft, of a transverse member mounted thereon and rotatable there-

with, two mixing vessels mounted on said member and having their axes coincidental with the axis of the shaft, each vessel having at its outer end a single opening for receiving and discharging its contents, means for rotating said shaft, member and vessels around the axis of the shaft, a toothed supporting frame in which the shaft is rotatively mounted, a pinion engaging said toothed frame, means for rotating said pinion, and a support on which the frame is revoluble in a plane at an angle to the plane of rotation of the vessels around the axis of the shaft.

5. In a mixing machine, the combination with two mixing vessels disposed with their axes in line, and having each at its outer end a single opening for receiving and discharging the contents thereof, and each vessel having a plurality of blades on its inner periphery, of means for revolving the vessels in two planes of revolution disposed at an angle to each other.

6. In a mixing machine, the combination with two mixing vessels disposed with their axes in line, and having each at its outer end a single opening for receiving and discharging the contents thereof, the walls of each vessel converging toward the opening therein, and each vessel being provided on its inner periphery with a plurality of blades, of means for revolving said vessels in two planes of revolution disposed at an angle to each other.

7. In a mixing machine, the combination with two mixing vessels disposed with their axes in line, and having each at its outer end a single opening for receiving and discharging the contents thereof, the walls of each vessel converging toward the end opening, and each vessel being provided with a plurality of blades on its inner periphery, of a frame in which the vessels are axially supported, means for revolving the vessels around their axes on said frame, and means for revolving the frame in a plane at an angle to the plane of revolution of the vessels around their axes.

8. In a mixing machine, the combination with two mixing vessels disposed with their axes in line, and having each at its outer end an opening for receiving and discharging the contents thereof, of a frame comprising two vertical parallel gear wheels and suitable bars connecting said wheels, means for rotatively supporting said vessels in said frame with their axes at an angle to the axes of the gear wheels, means for revolving said vessels around their axes, a support on which the frame is revoluble around the axes of the gear wheels, two pinions engaging said gear wheels, and means for rotating said pinions.

9. In a mixing machine, the combination with two mixing vessels, each having an axial opening for receiving and discharging its contents, and the vessels being mounted on a common axis and disposed with the said

- axial openings in diametrically opposite positions, of means for revolving the vessels around their axes, and means for reversing endwise the positions of the vessels.
- 5 10. In a mixing machine, the combination with two mixing vessels, each having an axial opening for receiving and discharging its contents, the vessels being mounted on a common axis and disposed with their 10 axial openings in diametrically opposite positions, the walls of each vessel converging toward its axial opening, of means for revolving the vessels around their axes, and means for reversing endwise the positions of the vessels.
- 15 11. In a mixing machine, the combination with two mixing vessels, each having an axial opening for receiving and discharging its contents, the vessels being mounted 20 on a common axis and disposed with their axial openings in diametrically opposite positions, the walls of each vessel converging toward its axial opening, and a plurality of blades arranged around the inner wall of 25 each vessel, of means for revolving the vessels around their axes, and means for reversing endwise the positions of the vessels.
12. In a mixing machine, the combination with two mixing vessels, each having 30 an axial opening for receiving and discharging the contents thereof, the vessels being mounted on a common axis and disposed with their axial openings in diametrically opposite positions, and a plurality of blades ar- 35 ranged around the inner wall of each vessel, of means for revolving the vessels around their axes, and means for reversing endwise the positions of the vessels.
13. In a mixing machine, the combina- 40 tion with two mixing vessels, each having an axial opening for receiving and discharging its contents, the vessels being mounted on a common axis and disposed with their axial openings in diametrically opposite positions, 45 and a plurality of radial blades on the inner
- wall of each vessel, of means for revolving the vessels around their axes, and means for reversing endwise the positions of the vessels.
14. In a mixing machine, the combination with two mixing vessels, each having an axial opening for receiving and discharging its contents, the vessels being mounted on a common axis and disposed with their axial openings in diametrically opposite positions, the walls of each vessel converging toward its axial opening, and a plurality of radial blades on the inner wall of each vessel, of means for revolving the vessels around their axes, and means for reversing endwise the positions of the vessels. 50
15. In a mixing machine, the combination with a mixing vessel provided with a single end opening for receiving and discharging the contents, of an axial shaft, a transverse plate secured to the shaft and having the vessel secured at its closed end to the plate, means for revolving the plate and vessel around the axis of the shaft, and means for revolving the plate, vessel and shaft in a plane at right angles to said shaft. 55
16. In a mixing machine, the combination with a mixing vessel having a single end opening for receiving and discharging the contents, of a transverse plate to which the closed end of said vessel is secured, a rotary shaft disposed axially in the vessel and having secured to it said plate, means for rotating said shaft, plate and vessel around the axis of said shaft, a frame in which the shaft is rotatively mounted, and means for re- 60 70 75 80 85 volving the said frame in a plane at right angles to the plane of rotation of the shaft.
- In testimony whereof I have signed my name to this specification in the presence of two subscribing witnesses.
